(57) **CLAIM**

The ornamental design for a trash can, as shown and described.

DESCRIPTION

FIG. 1 is a top, front, left-side perspective view of a trash can embodying our new design, the indefinite line breaks being omitted from this figure;

FIG. 2 is a top, rear, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The trash can in accordance with the present design can have any length, as indicated by the variable line breaks in FIG. 1, 2, and 5-8. Additionally, all features illustrated in phantom line form no part of the claimed subject matter.
